UNITED STATES PATENT OFFICE.

MAX F. HALLER, OF MENLO, WASHINGTON.

RAIL-JOINT.

1,117,038.

Specification of Letters Patent.

Patented Nov. 10, 1914.

Application filed March 5, 1914. Serial No. 822,713.

To all whom it may concern:

Be it known that I, MAX F. HALLER, a citizen of the United States, residing at Menlo, in the county of Santa Clara and State of California, have invented certain new and useful improvements in Rail-Joints; and I do hereby declare the following to be a full, clear, and exact description of the invention, such as will enable others skilled in the art to which it appertains to make and use the same.

This invention relates to new and useful improvements in railroad rail joints, and has for its principal object to provide a device which will hold the ends of abutting rails in proper position and prevent the same from sinking or coming out of alignment.

Another object of the invention is to provide a joint chair in which the ends of the rails will be securely held together to eliminate the usual space occurring between the ends of rails which causes said ends to become worn and also is exceedingly wearing on the rolling stock.

Still another object of the invention is to provide a joint chair which is provided with an extension to engage the under side of the rail head and strengthen the same to prevent it from twisting.

With these and other objects in view, the invention consists in the novel combination and arrangement of parts as will be fully set forth in the following specification and accompanying drawings, in which,

Figure 1 is a side view in elevation of a joint chair constructed in accordance with this invention, Fig. 2 is a longitudinal sectional view of Fig. 1, and, Fig. 3 is a transverse sectional view taken on line 3-3 of Fig. 1.

Referring now to the drawings by characters of reference, the numerals 1 and 2 designate generally the ends of abutting rails, each of which is provided with the recess 3, and the open ends of the recesses are provided with the rounded walls 4 as clearly shown in Fig. 2, which are arranged to act as guides for placing the rails in place when the device is to be put in use.

The rail joint which is designated generally by the numeral 5 preferably comprises a pair of angle plates 6 which are arranged to abut the under side of the heads of the rails, and form a support therefor, said angle plates being also provided with

the flange engaging members as clearly shown in Fig. 3 which terminate at their free ends in the off-set angular extension 7 as will be clearly seen upon referring to the drawings. Secured to the angle plates in the web engaging portion and intermediate the ends of said angle plates is provided the connecting member 8 which is arranged to fit within the recesses formed in the rails and thereby prevent said rails from coming out of alignment.

A suitable chair designated generally by the numeral 9, is provided and comprises the base plate 10 having the bent back portion 11 which is arranged to engage one of the flange engaging members of the angle plate 6 as clearly illustrated in Fig. 3. The opposite edge of the base plate 10 is bent back upon itself and arranged to engage the angular extension 7 and is again bent upwardly as at 12 to form the angularly extending portion having the angular extension 13 which abuts the under side of the head of the rail.

It will be evident from the foregoing that in use the rails which are to be joined are provided with the recesses 3 and the ends of the rails slipped between the angle plates 6 so that the portion 8 lies in the recesses 3 and holds the rails in direct alignment. The chair is then slipped over the whole and the device will then appear as illustrated in the drawings, thereby forming a tight and efficient rail joint without the use of nuts or bolts which may be easily placed in position and which will hold the rails firmly in the desired position without necessitating the use of nuts and bolts and also without necessitating any loss of time in placing the device in position.

While in the foregoing there has been shown and described the preferred embodiment of this invention, it is to be understood that such changes may be made in the combination and arrangement of parts as will fall within the spirit and scope of the invention as set out in the appended claim.

Having thus described my invention, I claim:

In a device of the character described, the combination with a pair of rails having abutting ends, and recesses in their ends, said recesses being in direct alignment, of a pair of angle plates held in spaced relation and adapted to engage the flanges and webs of the rails, a connecting element between

the angle plates and adapted to hold the same in spaced relation, said connecting element being adapted to fit the recesses in the ends of the rails to hold the rails in direct 5 alinement, angular extensions formed on the free edges of the angle plates, the opposite edges of said angle plates engaging the under side of the rail heads, and a joint chair adapted to surround the whole to hold 10 the device firmly in place, said chair being

provided with an angular extension adapted to engage the under side of the rail heads to prevent the same from twisting.

In testimony whereof I affix my signature in presence of two witnesses.

MAX F. HALLER.
